(57) CLAIM

The ornamental design for a dickie as shown and described.

DESCRIPTION

FIG. 1 is a perspective top front right view of a dickie, showing my new design;

FIG. 2 is a perspective top rear left view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof;

FIG. 9 is a cross-sectional view along the line 9-9 (see FIG. 3); and,

FIG. 10 is a cross-sectional view along the line 10-10 (see FIG. 3).

The broken lines show stitching on the dickie that forms no part of the claimed design.

1 Claim, 10 Drawing Sheets
